UNITED STATES PATENT OFFICE.

THERON H. WILLIAMS, OF CHICAGO, ILLINOIS, AND FRANCIS A. JACOBS, OF WARREN, OHIO, ASSIGNEES, BY MESNE ASSIGNMENTS, TO CHICAGO-CLEVELAND CAR ROOFING COMPANY, OF CHICAGO, ILLINOIS, A CORPORATION OF DELAWARE.

CAR ROOF.

Application filed May 31, 1923. Serial No. 642,397.

The invention relates to what are known as rigid all-steel car roofs, it being understood that wood may be employed in some cases for certain of the frame elements.

5 The invention has for its principle objects to lessen the cost of the roof as an entirety, and to simplify the construction of the same and reduce the cost of applying it to the roof frame; also to enclose by the 10 roof sheets all of the frame-fastening devices; also to unite the roof sheets rigidly and immovably with the carlines so that the sheets will not be subject to tearing under strain.

15 With such objects in view, as well as other advantages which may be incident to the use of the improvements, the invention consists in the parts and combinations thereof hereinafter set forth and claimed, with the 20 understanding that the several necessary elements constituting the same may be varied in proportions and arrangement without departing from the nature and scope of the invention.

25 In order to make the invention more clearly understood there are shown in the accompanying drawings means for carrying the same into practical effect, without limiting the improvements, in their useful applications, to the particular constructions which, for the purpose of explanation, have been made the subject of illustration.

In said drawings—

35 Figure 1 is a plan view of a rigid steel car-roof embodying the invention, certain of the parts being broken away for the purpose of reducing the length of the figure and of better showing some of the underlying parts.

40 Fig. 2 is an end elevation, looking endwise of the roof, of one of the end roof sheets.

Fig. 3 is a plan view of the same.

45 Fig. 4 is a cross section on line 4—4 of Fig. 3.

Fig. 5 is a plan view of one of the carlines.

Fig. 6 is a side elevation of the same.

50 Fig. 7 is a plan view of one of the intermediate roof sheets.

Fig. 8 is a cross section of the same on line 8—8 of Fig. 7.

Fig. 9 is an end view partly in section, of one corner of the roof, illustrating one of the corner cover plates.

55

Fig. 10 is a perspective view of the said corner of the roof, also illustrating said cover plate and contiguous parts, the end roof sheet being partly broken away.

Fig. 11 is a vertical section on a plane 60 longitudinal of the car illustrating the construction at or near the ridge of the roof, the same being taken on line 11—11 of Fig. 15.

Fig. 12 is a similar section taken on line 65 12—12 of Fig. 15.

Fig. 13 is a vertical sectional view of one of the clamps taken on line 13—13 of Fig. 14.

Fig. 14 is a side elevation of the same. 70

Fig. 15 is an elevation, showing one of the roof sheets and the ridge pole in section, illustrating the construction at and near the ridge of the roof, the view being taken on line 15—15 of Fig. 1.

75

Fig. 16 is a vertical sectional view on line 16—16 of Fig. 1 showing the connection of one of the carlines with a purlin.

Fig. 17 is a similar section on line 17—17 of Fig. 15. 80

Fig. 18 is a vertical section on line 18—18 of Fig. 1, and on a larger scale, and illustrating the attachment of the end of the carline to the steel side plate.

85

Fig. 19 is a similar view on line 19—19 of Fig. 1 illustrating the attachment of the eaves edge of the roof sheet to said plate.

Fig. 20 is a vertical sectional view on line 20—20 of Fig. 18. 90

Fig. 21 is a vertical sectional view similar to Fig. 18, but illustrating the application of the roof to a wooden side plate.

95

Fig. 22 is a side elevation of the same.

Referring to the drawings, 1 indicates the side plates of the roof frame. These are ordinarily or preferably of steel, but may be of wood as shown at 1^a in Fig. 21. In the former case the side plate is or may be an angle iron having a vertical web 2 and a top flange 3, the latter somewhat inclined to correspond with the pitch of the roof. Attached to the side plates 1 are end plates 4, which may be of steel of angle shape, as shown in plan view at the left end of Fig.

100

1 formed with a top flange 5 and vertical web 6, the ends 7 of the latter (Fig. 1) being bent into parallelism with and riveted to the webs 2 of the side plates.

5 The carlines are indicated at 8 and are of steel of inverted channel shape, formed with top webs 9, side webs 10 and outstanding bottom flanges 11 (Fig. 17). These carlines extend from side of the roof and 10 are secured at their ends to the flanges 3 of the side plates by rivets 12 (Fig. 18) or by bolts 12^a (Fig. 21), passing down through the widened ends 13 of the flanges 11 (Fig. 1).

15 The contour of the carlines from end to end is suitably arched or hipped to give the desired shape to the roof, and their webs 10 are downwardly inclined and flared away from each other.

20 The carlines may carry and be strengthened by sheet-supporting purlins 14 and a ridge pole 15, these parts being preferably but not necessarily of wood. The purlins are attached at their ends to the flanges 5 of the end plates by bolts 16 (Fig. 1), and to the webs 9 of the carlines by bolts 17 (Figs. 1 and 16).

25 The ridge pole is similarly attached to the carlines by bolts indicated at 18 (Figs. 1 and 15) and to the end plates by bolts 19. An end fascia may be used as shown at 24 (Figs. 1 and 10); and with wooden side plates a side fascia 25 (Figs. 21 and 22).

30 Such being the preferred or a suitable structure of roof frame, the sheets or plates to be fitted and secured thereon to make the roof sheathing will now be described.

35 The roof sheathing consists of a series of intermediate roof sheets 20, each extending between, engaging and supported by a pair of the carlines, and of end sheets 21 similarly covering the spaces from the end plates to the end carlines. These sheets, each extending across the car from side plate to side plate, lap over one another shingle fashion, proceeding from one end of the roof to the other, and one of the end sheets under-laps its contiguous intermediate sheet and the other end sheet over-laps its contiguous sheet. Each intermediate sheet 20 is bent along one of its edges, to form a channel 22 which embraces and fits a carline; and is similarly bent along its other edge to form a channel 23 which embraces and fits outside of a channel 22 of the next sheet when the latter is in place on a carline (Fig. 17). The over-lapping channels 23 are consequently, if the sheets be shaped to the best advantage, a little wider than the under-lapping channels 22, by about twice the thickness of the metal of which the sheets are made. Each of said roof sheet channels flares downwardly to correspond with the said shape of the carline side webs 10, and from end to end,

40 across the roof is shaped to fit the arched or other contour of the carline (Fig. 2). The end sheets are similarly formed along one edge only, with a channel (Fig. 3), one end sheet having an under-lapping channel 70 22 and the other an over-lapping channel 23. Along these channels and at a little distance therefrom the bodies of the roof sheets are upwardly bent, recessed or embossed, as shown at 26, for a distance equal 75 to the thickness of the carline flanges 11, so as to enclose said flanges and also have the under surfaces of their main portions at the level of the under sides of the carlines, and in contact with the tops of the side 80 plates; and with the ridge pole and purlins when the last mentioned elements are comprised in the roof frame. It may be here stated that by making the roof sheets of thicker metal, of self-supporting strength, 85 the ridgepole or purlins or both may be dispensed with, and the invention is not limited, in all of its applications, to the use therewith of a ridge pole or of purlins or of both of said frame elements. 90

45 In a roof of this rigid character, and especially when purlins or ridge pole or both are dispensed with, it is of great importance to secure the roof sheets to the carlines by an attachment of a strong and unyielding character, and which will not cause disruption of the roof sheets at the points of attachment when strains are imposed on the sheets; and for these objects it is further preferable to attach the roof sheets to the carlines at points 95 near the general level of the roof. The present invention obtains these results to a materially improved degree and by improved means, as will now be described. 29 indicates the roof sheet clamps (Figs. 13 and 14) formed of metal having sufficient resiliency to yield a little so as to apply the securing pressure gradually and evenly and yet so as not to release the roof sheets by any pull of the latter. These clamps, which are of 100 greater rigidity than the roof sheets and thus provide for firmly clamping the latter to the carlines, are formed to embrace the carlines, and the channels 22, 23 of the roof sheets thereon, by jaw elements 30 connected by a top part 31. The inner faces of the jaw elements or sides 30 of the clamps diverge downwardly somewhat more acutely than the sides of the cooperating carlines, thereby enabling the roof sheets to be 105 securely clamped to the carlines near the general level of the roof. The top of the clamp 29 is formed with a bolt perforation 32 which latter is or may be surrounded by an upward embossment 33 of the top. The manner of application of these clamps is shown best in Figs. 11 and 12. In these two figures the clamps are essentially the same, the securing bolts 34' in Fig. 11 being elongated upwardly and provided with top nuts 110 120 125 130

35 for the attachment of the running board saddle 36. These bolts, and the equivalent bolts 34 of Fig. 12, pass down through said perforations 32 of the clamps 29, and 5 through corresponding perforations in the tops of the roof sheet channels 22, 23 and in the top webs 9 of the carlines and are drawn down tightly by nuts 37. This action of the nuts 37 draws the lower parts of the jaw 10 elements 30 downward so as to cause them to have wedging cooperation with the lower wider parts of the channels and carlines, thereby securing the interposed portions of the roof sheets by a strong pressure immovably to the roof frame. By preference the 15 lower ends of the jaw elements are interiorly rounded as shown at 38 to facilitate said application of the clamps, and so as not to present a tearing or cutting edge or angle 20 to the secured parts of the roof sheets; and the perforation of the over-lapping channel is formed with a water-excluding neck or flange 39; and the bolt has a tapered enlargement 40 which wedges into said flange; and 25 a compressible means such as a lead plate or gasket 41 is interposed between the over-lapping channel and the clamp element 31 so as to very tightly hold down the roof sheet channels irrespective of the pressure of the 30 enlargement 40 in the flange 39; and the bolts are formed with reduced portions 42 by which they are permanently held in the clamps and from turning therein, in a manner clearly shown in the drawings; and nut locks 43 are applied to the nuts 37. These 35 preferred features are of material improvement and advantage but are not essential to all uses of the invention.

When the bolts are elongated, as seen in 40 Fig. 11, upper enlargements 44 are formed on the bolts to engage and be riveted or compressed on to the tops 31 of the clamps in place of the bolt heads 45 shown in Fig. 12.

45 The roof sheets may be further secured to the roof frame by short bolts 46 which pass through their eaves ends and through the flange 3 of the side plate (Fig. 19). The heads of these bolts are recessed as at 50 47 to receive upturned flanges 48 formed around the bolt holes in the roof sheets. The heads of these bolts are seated on compressible lead plates or washers 49 which surround said flanges. The bolts are drawn 55 tightly down by nuts 50, and the ends of the bolts are upset as at 51 to prevent their accidental unscrewing.

10 The extreme eaves edges of the roof sheets are bent down over the outer edge of the flange 3 into depending position as shown at 52. These depending edges of contiguous roof sheets lap one another as shown in Fig. 22.

15 If the roof be applied to wooden side plates (Figs. 21 and 22) the bolts 46 may

be dispensed with, the depending flanges 52 made a little longer and bolts 53 employed (Fig. 22) which pass horizontally inward through the said flanges and to the inner faces of the plates. These bolts may be 70 hollowed and fit over roof sheet hole flanges and bear on lead washers, as above described in the case of the bolts 46. The end sheets are similarly flanged down at the ends of the roof over the end fascia, as shown at 54 75 (Fig. 10).

It is important that the roof sheathing as a whole have an even, flat and extended bearing by the under faces of its parts on the frame elements, especially the carlines. 80 This object is attained by forming the roof sheets with upward embossments enclosing the upwardly projecting parts of the fastening devices which unite the frame elements with each other. The top parts of the roof sheet channels are thus formed with embossments 55 (Fig. 15) to receive and enclose the heads of the ridge pole bolts 18; and with embossments 56 for the heads of the purlin bolts 17 (Fig. 85 16). The lower parts of the roof sheets are formed with embossments 57 for the carline rivets 12 (Fig. 18) or bolts 12^a (Fig. 21). These embossments are also shown in the plan view of one of the main sheets (Fig. 9). The roof sheets are thus enabled to have extended flat bearings irrespective of the parts of said bolts which project up above the carlines, and also said fastenings are 90 perfectly protected from the weather.

100 It will be understood that any desired or necessary number of the clamps 29 may be applied on the roof sheets over each carline. In the construction illustrated I have shown the application of four such clamps per carline, enough to clearly illustrate my invention and the manner of use of such clamps. In the illustrated construction two of the clamps are applied under the running board saddle, at or near the ends thereof, and another of the clamps is applied near the position of each purlin, at a location about midway between the running board saddle and the eaves of the roof.

110 Each of the corners of the roof is or may be provided with a corner cover plate 58, best seen in Figs. 9 and 10. This plate is formed with a longitudinal inwardly extending flange 59 which engages over the outer edge of the side plate flange 3. Thence the cover plate extends longitudinally, and beyond the termination of said flange 3 and past the inner side of the end fascia 24. The cover plate is further provided with an inwardly extending web 60 arranged under the flange 3 and extending to the side sheathing, from which a vertical plate 61 extends down on the side of the car. The cover plate is secured in position by the depending roof sheet flange 52, as seen in Fig. 9, and also by a screw or bolt 120 125 130 135 140

62 which extends through an end bracket part 63 of the cover plate and into the end fascia. This cover plate closes an interstice in the construction caused mainly by the 5 flanges 7 of the end plate passing under the flange 3 and the top flange 5 of the end plate being arranged at a level with the top of the side plate, and the cover plate prevents any rain being dashed into the interior of the 10 car in heavy storms.

It is thought that the invention and many of its attendant advantages will be understood from the foregoing description, and it will be apparent that various changes 15 may be made in the form, construction and arrangement of the parts without departing from the spirit and scope of the invention, or sacrificing any of its material advantages, to form hereinbefore described being merely 20 a preferred embodiment thereof.

What is claimed is—

1. In a rigid steel car-roof, the combination of carlines, roof sheets having parts arranged against the sides of the carlines, 25 and wedging means for forcing said parts of the roof sheets towards the sides of the carlines so as to rigidly clamp said sheets to the carlines.

2. In a rigid steel car-roof, the combination of carlines, roof sheets having parts arranged against the sides of the carlines, and wedging means for forcing said parts of the roof sheets towards the sides of the carlines at points near the general level of 35 the roof so as to rigidly clamp said sheets to the carlines.

3. In a rigid steel car-roof, the combination of carlines, roof sheets having parts arranged against the sides of the carlines, 40 and wedging clamps embracing the carlines and said parts of the roof sheets for forcing the latter towards the lower portions of the sides of the carlines so as to rigidly clamp the roof sheets thereto.

4. In a rigid steel car-roof, the combination of carlines, roof sheets having parts embracing the carlines, and wedging means for forcing said parts of the roof sheets immovably against the lower portions of the 50 sides of the carlines so as to rigidly clamp the roof sheets thereto.

5. In a rigid steel car-roof, the combination of carlines having their lower parts wider than their upper parts, roof sheets having interfitting upstanding channels which embrace the carlines, and clamping means pressing downwardly relative to the carlines for forcing the channel parts of the roof sheets towards the sides of the carlines to thereby clamp the roof sheets to the carlines.

6. In a rigid steel car-roof, the combination of carlines upstanding above the general level of the roof, and having their lower parts wider than their upper parts, roof

sheets having upstanding channels which embrace the carlines, and clamping means pressing downwardly relative to the carlines for wedging said channels of the roof sheets towards the two opposite sides of the carlines to thereby clamp the roof sheets to the carlines. 70

7. In a rigid steel car roof, the combination of carlines having upwardly tapering sides, roof sheets having parts embracing the entire sides and top of the carlines, downwardly flaring clamps embracing the said parts of the roof sheets and the carlines within the same, and means for forcing the clamps towards the carlines and tightly 80 against one of the roof sheets to unite said sheets rigidly and immovably with the carlines.

8. In a rigid steel car-roof, the combination of carlines, roof sheets having parts arranged against the sides of the carlines, means for pressing said parts of the roof sheets towards the sides of the carlines at points near the general level of the roof 85 revolving bolts having shoulders both above and below said pressing means and extending to the undersides of the carlines. 90

9. In a rigid steel car-roof, the combination of carlines, roof sheets having parts embracing the sides of the carlines, and clamps embracing the carlines and said parts of the roof sheets and holding the latter rigid with respect to the sides of the carlines, and bolts extending from said clamps through perforations in the roof sheets to the under sides 95 of the carlines, said bolts having enlargements for wedging into said perforations. 100

10. In a rigid steel car-roof, the combination of carlines having upwardly tapering 105 sides, roof sheets having parts embracing the carlines, downwardly flaring clamps embracing the said parts of the roof sheets and the carlines within the same, and bolts extending from said clamps to the under sides 110 of the carlines for forcing the clamps towards the carlines for securing the lower portions of the said parts of the roof sheets rigidly and immovably with the carlines.

11. In a rigid steel car-roof, the combination of carlines, roof sheets having parts embracing the carlines, clamps operating at the two opposite sides of the carlines for rigidly clamping said parts of the roof sheets to the sides of the lower half of the carlines, bolts extending from said clamps through said parts of the roof sheets and through the carlines, and compressible means between the top parts of the clamps and said parts of the roof sheets for holding down said parts. 115 120 125

12. In a rigid steel car-roof, the combination of a roof frame, upwardly projecting fastening devices connecting the elements of 130 said frame, and roof sheets laid on and se-

cured to said frame and formed with upward registering embossments enclosing the upwardly projecting parts of said frame-fas-

tening devices.

5 13. In a rigid all steel car roof in combination: side plates; inverted channeled shaped carlines having a substantially flat top web and downwardly extending outwardly flaring sides terminating in lateral flanges; roof sheets extending across the car from side plate to side plate, and secured thereon, the sides of said roof sheets terminating in upwardly projecting side flanges of inverted channel form, said side flanges being formed similarly to the inverted channel portion of said carlines to fit over said channeled portion in lapped formation so that each of said side flanges encloses the entire inverted channeled portion of said carlines, and wedging means for forcing the channel parts of the roof sheets towards the carlines to secure the roof sheets rigidly thereto.

25 14. In a rigid steel car-roof, the combination of carlines, roof sheets having parts embracing the carlines, wedging devices for rigidly clamping said parts of the roof sheets to the carlines and detachable means for adjustably forcing said devices towards the carlines.

35 15. In a rigid steel car-roof, the combination of carlines, roof sheets having parts arranged against the sides of the carlines, and means for wedging said parts of the roof sheets into rigid clamped relation with the sides of the carlines involving bolts extending from the said means to the undersides of the carlines.

40 16. A rigid steel roof for railway cars involving carlines, clamps embracing said carlines, each of said elements having diverging sides, roof sheets having portions interposed between the carlines and clamps, and means for forcing the clamps downwardly towards the carlines, the divergence of the sides of the clamps being less than that of the carlines, and the clamps being so formed and arranged that upon being moved downwardly they will secure the roof sheets rigidly to the carlines.

45 17. A rigid steel car roof for railway cars involving carlines, substantially rigid clamps embracing said carlines, each of said elements having downwardly diverging sides, roof sheets having portions interposed between the clamps and carlines, the interposed portions of the roof sheets being less rigid than the clamps, and means for forcing the clamps downwardly towards the carlines to clamp the roof sheets securely to the latter.

50 18. In a rigid steel roof for railway cars, the combination of carlines having downwardly diverging sides, substantially rigid

clamps embracing the carlines having downwardly diverging sides, and roof sheets having portions interposed between said carlines and clamps, the interposed portions of the said sheets being of less rigidity than the 70 clamps, the divergence of the sides of the clamps being less than that of the sides of the carline so that the clamps upon being forced downwardly will clamp the said portions of the roof sheets rigidly to the car- 75 lines.

19. A rigid steel roof for railway cars involving carlines having diverging sides, roof sheets having overlapping portions embracing the carlines, clamps having diverging 80 sides embracing the said overlapped portions of the sheets, and means for forcing the clamps downwardly towards the carlines, the divergence of the sides of the clamps being less than that of the carlines, and the 85 clamps being so formed and arranged that upon being moved downwardly they will secure the roof sheets rigidly to the carlines.

20. A rigid steel roof for railway cars involving carlines having downwardly diverging 90 sides, roof sheets having overlapping portions embracing the carlines, clamps having downwardly diverging sides embracing the said overlapped portions of the sheets, the carline embracing portions of the roof 95 sheets being less rigid than the clamps, and means for forcing the clamps downwardly towards the carlines to clamp the sheets securely to the carlines.

25 21. A rigid steel roof for railway cars involving carlines having downwardly diverging sides, roof sheets having overlapping portions embracing the carlines, substantially rigid clamps having downwardly flaring 100 sides embracing the said overlapped portions 105 of the sheets, the carline embracing portions of the roof sheets being of less rigidity than the clamps, and means for forcing the clamps downwardly towards the carlines, the divergence of the sides of the clamps being less than that of the sides of the carlines 110 so that the clamps upon being forced downwardly will secure the said portions of the roof sheets rigidly to the carlines.

30 22. A rigid steel roof for railway cars involving carlines having downwardly diverging sides, roof sheets having overlapping portions embracing the carlines, clamps arranged over the said overlapped portions of the sheets and having oppositely downwardly diverging sides in engagement with one of the overlapped sheets, and means for forcing the clamps downwardly towards the carlines, the divergence of the sides of the clamps being less than that of the sides of the carlines, and the clamps being so formed 120 and arranged that upon being forced downwardly they will secure the said portions of the roof sheets rigidly to the carlines adjacent 125 the main level of the roof.

23. A rigid steel roof for railway cars involving carlines having downwardly diverging sides, roof sheets having overlapping portions embracing the carlines, clamps having downwardly flaring sides embracing the said overlapped portions of the roof sheets, the rigidity of each of the clamps being greater than the combined rigidity of the overlapping portions of the roof sheets 5 underlying the clamp, and means for forcing said clamps downwardly to clamp the said portions of the sheets securely to the carlines.
24. A rigid steel car roof for railway cars involving a carline having oppositely disposed sides, roof sheets having portions arranged in overlapped relation on the carline, and a member for securing the said sheets to the carline, said member having a 10 stud, the overlapping portions of the roof sheets having registering apertures to receive 15
- 20

said stud, one of said apertures being bounded by a marginal flange, said stud having a tapered portion firmly engaging the flange of said last named aperture when the securing member is in assembled position. 25

25. A rigid steel roof for railway cars involving a carline having oppositely disposed sides, roof sheets having portions arranged in overlapped relation on the carline, and a member for securing the said sheets to the carline, said member having a stud, the overlapping portions of the sheets having registering apertures to receive the said stud, said stud having a longitudinally tapered 30 portion adapted to engage the bounding wall of one of said apertures when the securing member is in assembled position. 35

In testimony whereof we have hereunto set our hands.

THERON H. WILLIAMS.
FRANCIS A. JACOBS.
